UNITED STATES PATENT OFFICE

CURTIS CARSON, OF WALTERBORO, SOUTH CAROLINA, ASSIGNOR OF ONE-HALF TO G. E. GUILFORD, OF WALTERBORO, SOUTH CAROLINA

TOY

Application filed May 13, 1930. Serial No. 452,105.

The present invention relates to a toy.

In accordance with the invention, a toy is provided including a handle and a pair of elements secured to the handle by means of flexible elements or cords. By proper manipulation of the handle, the elements may be rotated in opposite directions at the same time. The elements carry sound producing devices, which are actuated by the outward radial movement of the air, due to the action of centrifugal force. The construction of the elements is such that the cords are secured thereto in a simple and reliable manner.

15 In the accompanying drawings, forming a part of this specification, and in which like numerals are employed to designate like parts throughout the same,

Figure 1 is a perspective view of the toy, 20 in use,

Figure 2 is a similar view of one of the rotatable elements,

Figure 3 is a central vertical longitudinal section through the same, and,

25 Figure 4 is a transverse section taken on line 4—4 of Figure 1.

In the drawings, wherein for the purpose of illustration, is shown a preferred embodiment of the invention, the numeral 5 designates a handle which is preferably tubular to receive the ends of flexible elements or cords 6 and 7, which are clamped therein by any suitable means. The cord 7 is longer than the cord 6, as shown.

35 The numeral 8 designates rotatable elements, which are identical, and a description of one will suffice for both. Each rotatable element 8 may be formed of wood or any other suitable material and embodies a body portion 9, provided with a longitudinal recess 10. At its inner end, this recess leads into a sleeve 11, integral with the body portion 9. The outer end of the flexible element or cord is passed through the recess 11, 40 and is provided at its inner end with a knot 12, preventing separation of these parts. At its outer end, the body portion 9 is provided with a larger sleeve 13, preferably formed integral with the body portion. This sleeve 45 is annular in cross section, and is provided at

its outer end with an outwardly projecting annular flange 14.

An air actuated sound producing device is mounted upon the outer end of the sleeve 13 and embodies a disc 15, having an annular 55 ring 16 formed integral therewith, to fit over the flange 14, and the edge of this ring is bent inwardly, producing a locking flange 17, engaging behind the flange 14. The disc 15 is provided with openings or slots 18, covered 60 by vibratory keys 19, as are used in the ordinary mouth organ, and these keys are attached to the disc 15, as shown at 20.

In operation, the handle 5 is held in the right hand, and the element 8 secured to the 65 cord 7, is held in the left hand. By proper manipulation of the handle 5, the element 8 secured to the cord 6, is swung or rotated counter-clockwise, and the element 8 secured to the cord 7, is now started in a swinging 70 movement in a clockwise direction, and the rotation of the two elements 8, in opposite directions, is maintained by a proper up and down movement of the handle 5. As the speed of rotation of the two elements 8 increase, the air travels outwardly through the 75 sleeve 13, due to the action of centrifugal force, and the keys 19 are vibrated for producing a humming or musical sound.

It is to be understood that the form of the 80 invention, herewith shown and described, is to be taken as a preferred example of the same, and that various changes in the shape, size and arrangement of parts, may be resorted to, without departing from the spirit 85 of the invention, or the scope of the subjoined claim.

What is claimed is:

A toy of the character described, comprising a handle, flexible elements secured to the handle, and rotatable elements carried by the flexible elements, each rotatable element comprising an elongated body portion having a longitudinal recess upon its side, a sleeve formed upon the inner end of the body portion and extending longitudinally of the body portion and having a bore leading into the recess, said sleeve receiving the outer end of the flexible element which is provided with an enlargement outwardly of the sleeve and 95 100

positioned within the recess, a second sleeve formed upon the outer end of the body portion and extending longitudinally of the body portion and having a bore leading into the recess, and an air actuated sound producing device mounted upon the second sleeve and actuated by the outward radial travel of air through the sleeve.

In testimony whereof I affix my signature.
CURTIS CARSON.
